UNITED STATES PATENT OFFICE.

JOHN M. LEVANGIE, OF SOUTH BRAINTREE, MASSACHUSETTS, ASSIGNOR TO UNITED SHOE MACHINERY CORPORATION, OF PATERSON, NEW JERSEY, A CORPORATION OF NEW JERSEY.

SHOE-SEWING MACHINE.

1,342,685.

Specification of Letters Patent.

Patented June 8, 1920.

Application filed July 27, 1918. Serial No. 246,962.

To all whom it may concern:

Be it known that I, JOHN M. LEVANGIE, a citizen of the United States, residing at South Braintree, in the county of Norfolk 5 and State of Massachusetts, have invented certain new and useful Improvements in Shoe-Sewing Machines; and I do hereby declare the following to be a full, clear, and exact description of the invention, such as 10 will enable others skilled in the art to which it appertains to make and use the same.

The present invention relates to shoe sewing machines and is intended primarily as an improvement on inseam shoe sewing machines which are adapted to sew welted or 15 turn shoes. An example of this class of machines is fully illustrated in the patent to Eppler No. 1,108,560, issued August 25, 1914.

Machines of this class as heretofore constructed have been provided with a back rest slide or slide-gage, against the forward end of which the shoe is held during the sewing operation and which at a certain period of each cycle of operations is held locked in position so that the shoe cannot be pulled backwardly by the action of the stitch forming devices during the formation of a stitch. In machines as heretofore constructed, the end of the back rest slide which comes in contact with the shoe has been made of metal, and it has been found in practice that the metal end of the back rest slide is liable to damage the leather in the shoe upper. To overcome this difficulty, the operators of 30 sewing machines of this character sometimes cover the forward end of the back rest slide with leather or cloth.

It is an object of this invention to provide means whereby a pad or buffer may be firmly 40 secured on the forward end of the back rest slide, and may be quickly and easily changed by the operator whenever a change becomes necessary or desirable. With this object in view, a feature of the invention resides in the provision of a clamping device secured to the forward end of the back rest slide which may be readily opened and closed, so that a pad of felt or similar substance may be inserted in the clamping device when it is 45 open, and may be held securely in position on the end of the back rest slide when the clamping device is closed.

A further feature of the invention resides in the provision of ears or projections on

one of the clamping members which constitute the clamping device, to hold the pad against lateral movement in the clamping device.

An additional object of the invention is to provide means for holding the pad stiff within the clamp. To this end, the invention contemplates the provision of a steel pin extending through that portion of the felt pad which is held within the clamp, said pin having its ends flush with the felt so that 65 said ends will be engaged by the clamp as it is closed.

Other features of the invention consist of certain constructions, arrangements and combinations of parts, the advantages of 70 which will be obvious to one skilled in the art.

The various features of the invention will be clearly understood from the following detailed description and the accompanying 75 drawings, in which:—Figure 1 is a left-hand side elevation of a shoe sewing machine embodying this invention; Fig. 2 is a front elevation of the clamping device showing the device closed; Fig. 3 is a rear elevation of the 80 clamping device showing the device open; and Fig. 4 is a longitudinal section through the pad and the clamping device, looking from the left.

The sewing machine illustrated in the 85 drawings is provided with the usual stitch forming instrumentalities, comprising a curved hook needle 2, a looper 4, a thread finger 6, a welt-guide 8, and a back rest slide 10.

The back rest slide, as illustrated, is similar to that shown in the patent to Eppler, above referred to, with the exception of the pad and clamping device therefor. According to the present invention, there is provided a pad 28 of felt or similar substance which is secured to the forward end of the back rest slide and against which the shoe is adapted to be held during the sewing operation. This pad is secured to the forward 100 end of said slide by means of a clamp comprising two clamping members relatively movable toward and away from each other so that the clamp may be closed to hold a pad securely against movement, or may be 105 opened and a new pad inserted. The clamping device comprises a clamping member 30 which is pinned to a plate 32 formed in-

tegrally with a screw 34 which is screwed into the forward end of the back rest slide 10. Coöoperating with the clamping member 30 is a clamp member 36 which is movable relatively to the clamping member 30 so as to open and close the clamp. To enable the clamping member 36 to be moved in this manner, said clamping member has a tongue or projection 38 formed thereon which is received between the plate 32 and the fixed clamping member 30, said plate being cut away between its ends to form a recess in which the tongue 38 slides as the clamp is opened and closed.

15 The ends 40 of the plate 32 are of greater thickness than the middle part of said plate and the tongue 38 is held against lateral movement by said ends, which form the sides of the recess in which the tongue 38 slides. The clamping device is opened and closed by a cam lever 42 pivotally mounted on a pin 44 which is secured in the tongue 38. The cam surface of the lever 42 cooperates with the lower edge of the plate 32 and as the lever is moved from the position shown in Fig. 3 to that shown in Fig. 2, the engagement of said cam surface with the plate 32 enables the lever to slide the clamping member 36 relatively to the clamping member 30 to close the clamp.

30 The felt pad 28 has recesses 46 formed in the upper and lower surfaces of said pad and when the clamping device is closed by the cam lever 42, inwardly-bent projecting portions 48 and 50 formed on the clamping members 36 and 30, respectively, engage in said recesses and prevent any possible forward and rearward movement of the pad within the clamp. It is also desirable to hold the pad against any possible lateral movement and to this end the clamping member 30 has formed thereon two forwardly bent projecting portions 52 and 54 which engage the pad at its right and left ends.

35 As the clamping members are drawn together by the action of the cam lever 42, the squeezing action of the clamping device would cause the felt pad to be distorted or bent within said clamping members and would cause said pad to become loose therein unless some stiffening means were provided to prevent such action taking place. According to the present invention, there is provided a steel pin 58 extending through the felt pad in a substantially vertical direction just rearwardly of the recesses 46 formed in the pad. This pin is of such length that its ends are flush with the surface of the pad when the clamp is closed so that the clamping members engage the ends of the pin at such a time, and that portion of the felt which is held within the clamping members is prevented from being bent and distorted by the squeezing action.

The nature and scope of the present invention having been indicated and its preferred embodiment having been specifically described, what is claimed as new is:—

1. An inseam shoe sewing machine having, in combination, a back rest slide, a pad, and means for securing the pad to the forward end of the back rest slide, said means comprising a clamp and means for opening and closing the clamp. 70

2. An inseam shoe sewing machine having, in combination, a back rest slide, a pad, a clamp for securing said pad to the forward end of the back rest slide comprising two relatively movable clamping members, 80 and a cam lever for moving said members relatively to each other to open and close the clamp. 75

3. An inseam shoe sewing machine having, in combination, a back rest slide, a pad, 85 a clamp for securing said pad to the forward end of the back rest slide, comprising a clamping member fixed on said back rest slide and a clamping member slidably mounted thereon, and a cam lever pivoted on said slidably clamping member for opening and closing the clamp. 90

4. An inseam shoe sewing machine having, in combination, a back rest slide, a pad, and a clamp for securing said pad to the 95 forward end of the back rest slide, comprising two relatively movable clamping members, one of said clamping members having projections formed thereon to prevent longitudinal movement of the pad within the clamp. 100

5. An inseam shoe sewing machine having, in combination, a back rest slide, a pad, a clamp engaging a portion of said pad to secure said pad to the forward end of the 105 back rest slide, and means for stiffening that portion of the pad which is engaged by the clamp to prevent bending of the pad by said clamp.

6. An inseam shoe sewing machine having, in combination, a back rest slide, a pad, a clamp engaging a portion of said pad to secure said pad to the back rest slide, and a pin extending through the pad and engaged at its ends by said clamp when the 115 clamp is closed.

7. An inseam shoe sewing machine having, in combination, a back rest slide, a pad, a clamp for securing said pad to the back rest slide, comprising two relatively movable clamping members, said clamping members having inwardly extending projections formed thereon, means for moving the clamping members relatively to open and close the clamp, and a pin extending 120 through the pad and beneath said projections. 125
